(57) **CLAIM**

We claim the ornamental design for a aerosol generator holding sleeve, as shown and described.

DESCRIPTION

The FIGURE is a front view of a aerosol generator holding sleeve.

The FIGURE shows a portion of the aerosol generator holding sleeve, surrounded by dot dash broken lines, with the remainder shown in de-emphasized, reduced tonal value so as to illustrate environmental structure. The elements shown outside the dot dash broken lines form no part of the claimed design and are merely included to show environmental aspects thereof.

The dot dash broken lines in the drawing illustrate boundary portions of aerosol generator holding sleeve that form no part of the claimed design.

The FIGURE is illustrated to show contrasting appearance. Areas of the sleeve that appear in different shades of gray represent areas with contrasting appearances.

The aerosol generator holding sleeve as shown in the FIGURE lacks appreciable depth or thickness that can be depicted and accordingly, the front view is solely presented herein.
